(57) **CLAIM**

The ornamental design for a walking stilt, as shown and described.

DESCRIPTION

FIG. 1 is a perspective view of my walking stilt taken from the front right showing my new design;

FIG. 2 is a side view thereof taken from the right;

FIG. 3 is a front view thereof taken from the front; and,

FIG. 4 is a side view thereof taken from the right showing the step portion partially swiveled upwards.
